CARBURETOR CONTROL

Thomas M. Ball, Detroit, Mich., assignor to
Chrysler Corporation, Highland Park, Mich., a
corporation of Delaware

Application November 29, 1946, Serial No. 713,051

1 Claim. (Cl. 123—179)

1

This invention relates to improvements in carburetors for internal combustion engines.

More particularly the invention relates to automatic choke control means for providing a proper fuel and air mixture during cranking and idling of a cold engine.

Automatic choke controls which are operable in response to engine temperature are commonly provided on carburetors. A typical device of this type provides a bimetal element and means to expose this element to heat from the exhaust manifold. Expansion and contraction of the bimetal element is utilized to move a choke valve controlling the admission of air to the carburetor. These devices are inadequate to properly accommodate both cranking and initial idling of a cold engine. If the thermostatic choke control is adjusted so that the correct amount of air enters the carburetor for engine cranking, then an inadequate amount of air is present during engine idling. Similarly, if the thermostatic choke control is adjusted for engine idling then too much air is available for engine cranking under cold conditions. The different requirements of engine cranking and engine idling result from the fact that the lowest engine idling speed is many times the speed of engine cranking.

It is an object of my invention to provide means to assure a fixed choke valve position during engine cranking below a predetermined temperature. This means is adapted to overrule the thermostatic control under these conditions and to provide the optimum mixture for engine cranking.

It is a further object of the invention to provide a thermostatic control that is adjusted for the desired mixture for engine idling and to provide a supplemental means to overrule the thermostatic control to provide the proper mixture for engine cranking. The choke valve is drawn by said means to its substantially closed or engine cranking position and retained in this position during engine cranking below a predetermined temperature.

In the drawings:

Fig. 1 is a vertical section of a carburetor equipped with my invention and the associated intake and exhaust manifolds of an internal combustion engine;

Fig. 2 is a vertical section on the line 2—2 of Fig. 1;

Fig. 3 is a vertical section of the bimetallic element taken on the line 3—3 of Fig. 1;

Fig. 4 is a vertical elevation partly broken away and taken on the line 4—4 of Fig. 1; and

Fig. 5 is a wiring diagram including the starting motor and electric choke control means.

2

Referring to the drawings, the carburetor 10 is secured to the engine intake manifold 11. The carburetor comprises a body 12, an air horn 13, an insulator 14, and a body flange 15. These parts are assembled vertically and are provided with a tubular fuel mixture passage 16. The passage 16 has a restricted portion at 17 which is adapted to produce a Venturi effect in a manner well known in the art. A nipple 18 on body 12 is adapted to be connected by a fuel line, not shown, to a source of supply of fuel such as a fuel pump, not shown. The air horn 13 serves as an inlet to the fuel mixture passage 16. The egress of the fuel mixture from the passage 16 to the engine intake manifold is controlled by throttle valve 19.

The body portion of the carburetor is provided with a fuel reservoir 20. The intake of fuel from the nipple 18 is controlled by a needle valve 21 which is operated by a conventional float mechanism 22 which predetermines the fuel level in the reservoir.

The main fuel injection means controls the mixture of air with fuel passing through metering jet 23. Tubular passage 24 connects jet 23 with mixture chamber 16 at orifices 25. Tubular element 26 which is connected to the atmosphere by ducts, not shown, and is concentrically disposed within passage 24 provides means for mixing air with fuel in passage 24 in the usual manner.

Liquid fuel for engine idling is drawn by manifold vacuum from passage 27 through passage 28 and passage 29 to idling jet 30. Air for the idling jet 30 is drawn through orifice 31 in the side wall of passage 16 and downwardly from orifice 32 in the air horn through passage 29. A conventional choke valve 35 is pinned to a shaft 36 which is rotatably mounted transversely of the air horn. The position of the valve 35 in the air horn 13 may be varied by rotation of the shaft 36 and this position will determine the restriction to the passage of air from the air horn 13 through the mixture passage 16. The valve 35 is preferably mounted off center on the shaft 36 so that the weight of the valve and the passage of air will tend to maintain the valve in its open position. When the engine is being cranked by operation of the conventional starting motor, it is desirable to have the valve 35 substantially fully closed so that it blocks the air horn 13. Bleed hole 37 and a small spring-loaded valve 38 are provided to maintain a small flow of air into the mixture passage 16 under these conditions.

A chamber 40 provided on the side of the air horn 13 houses a bimetallic coil element 41 which

has one end 42 secured to the shaft 36 and its other end 43 secured to a fixed object such as the wall of the air horn. A tube 44 is connected to the housing 40 and extends into close proximity with the exhaust manifold of the engine. An opening 45 may be provided in the manifold for this purpose. The opening 45 is not, however, connected with the exhaust manifold passages and exhaust gases are not present in the opening 45. The tube 44 is provided with openings 46 adjacent the end portion within the opening 45. A passage 47 connects the housing 40 with the lower portion of the mixture passage 16. There is thus provided a means for circulating warm air taken from the vicinity of the exhaust manifold around the bimetallic element 41. The suction present in the intake manifold of the engine draws air from housing 40 through passage 47 and this air is replaced by warm air drawn from the opening 45 into the housing 40 through the tube 44. The temperature of the coil element 41 is thus dependent upon the engine operating temperature and the expansion and contraction of the coil element 41 rotates the shaft 36 to position the valve 35 in a position which is controlled by engine temperature.

The choke valve 35 and bimetallic coil element 41 may be adjusted so that under cold conditions the valve 35 will be moved to a partially closed position which is known to produce the optimum fuel mixture for engine idling conditions. This position is designated by the numeral 50 in Fig. 4.

When cranking the engine under similar conditions, it is desirable to have the choke valve 35 in an even further closed position designated by the numeral 51 in Fig. 4. Since the temperature of the bimetallic coil element 41 is the same under these two conditions, it is necessary to provide supplemental means to force the choke valve 35 to the position 51 under starting conditions. To accomplish this I have provided a solenoid 52 which is secured by bolts 53 to the air horn 13. The solenoid 52 is connected in parallel with the starting motor as illustrated in Fig. 5. The usual storage battery 53 through line 54 is connected to the starting motor 55. Line 56 connects the starting motor with a starter switch 57. Line 58 connects the starter switch with the battery 53. The solenoid 52 is connected in parallel across the lines 54 and 56 so that actuation of the starter switch 57 energizes both the motor 55 and the solenoid 52.

The shaft 36 supporting the choke valve 35 is journaled in the air horn 13 and is provided with a lever 60 keyed thereto. The lever 60 is formed from a magnetic material and when it is in the field of the solenoid 52 and the solenoid is energized by the operation of the starter switch 57, the lever 60 is attracted to the solenoid 52 and assumes the position designated by the numeral 61 in Fig. 4. When the lever 60 is in the position 61, the choke valve 35 is in the position 51. The choke valve 35 when in the position 51, completely blocks the passage in the air horn 13 and the

only air permitted to enter the mixture passage 16 comes through the bleed hole 31 and spring-controlled valve 38 in the choke valve 35. When the choke valve 35 is rotated sufficiently by the expansion of the bimetallic coil element 41 under warm conditions, the lever 60 is moved away from the solenoid 52 sufficiently so that the magnetic field of the solenoid 52 does not have the strength necessary to move the lever 60 to the position 61. Thus at some predetermined temperature through the influence of the bimetallic coil element 41 the lever 60 is moved out of operative relationship with the solenoid 52. Actuation of the solenoid 52 as an incident to operation of the starter switch 57 is, therefore, only effective below a predetermined temperature, to move the choke valve 35 to the position 51.

The bimetallic coil element 41 is thus adapted to control the position of the choke valve 35 between the limits illustrated by the position 50 and the full open position 62 illustrated in Fig. 4. The solenoid 52 and lever 60 are adapted to move the choke valve 35 to the position 51 in Fig. 4 providing that the solenoid 52 is actuated below a predetermined temperature when the lever 60 is in close proximity to the solenoid 52.

I claim:

In an internal combustion engine having a carburetor adapted to mix air and fuel and a self-starter adapted to crank said engine, a choke valve mounted upon a shaft and rotatable in said carburetor to regulate between limits the proportion of air in said mixture, a thermostatic device operable to control said valve by rotation of said shaft in response to changes in engine temperature within a predetermined temperature range, an electromagnetic device associated with said valve and operable to establish a predetermined fuel and air mixture within certain temperature limits included in said temperature range, said electromagnetic device including a stationary solenoid and an element keyed to said shaft and adapted to be attracted by said solenoid, said solenoid and said shaft being so positioned that rotation of said shaft beyond a predetermined limit in response to increased engine temperature removes said element from the effective field of said solenoid and means to energize said solenoid as an incident to each actuation of said self-starter.
